UNITED STATES PATENT OFFICE.

CARL M. WELTE, OF NEW YORK, N. Y., ASSIGNOR TO M. WELTE & SONS, INC., OF NEW YORK, N. Y., A CORPORATION OF NEW YORK.

CONTROLLER MECHANISM FOR MECHANICAL MUSICAL INSTRUMENTS.

1,252,064.

Specification of Letters Patent.

Patented Jan. 1, 1918.

Application filed December 11, 1913. Serial No. 805,916.

To all whom it may concern:

Be it known that I, CARL M. WELTE, a citizen of the United States, and a resident of New York, in the county of New York and State of New York, have invented certain new and useful Improvements in Controller Mechanism for Mechanical Musical Instruments, of which the following is a full, clear, and exact description, whereby anyone skilled in the art may make and use the same.

The invention relates to certain new and useful improvements in automatically operated musical instruments and is directed more particularly to the control mechanism, that is, the mechanism which controls the operation of the playing devices such as the perforated music sheet and its winding and re-winding mechanisms and the control of the tracker-board which is used in conjunction with a perforated music-sheet.

The invention is applicable generally to musical instruments wherein the operation of the sound-producing devices is actuated and controlled by a perforated music sheet, card, tablet or the like, which is moved over a tracker-board having ducts or conduits which are suitably connected with pneumatically actuated devices.

In instruments of this character a single sheet of perforated music is carried by two rollers arranged on opposite sides of the tracker-board and in playing said sheet, it is unwound from one roller and wound upon the other roll.

The movement of the music sheet during the playing operation is, of course, quite slow and although the rewinding of the sheet after it is played may be accomplished with considerable speed, it is obvious that there is a pause in the operation of the instrument after a certain selection or number of selections have been played.

To over-come this lost time it has become a practice to employ a plurality of tracker-boards, each of said trackers having an independent pair of music rolls for playing and re-winding the music sheet. In such devices, provision has been made for re-winding one music-sheet during the playing of another independent music sheet so that

to all purposes and intents a continuous playing of the instrument has been possible. In such devices, however, it has been necessary to provide a somewhat complicated system of winding and re-winding mechanism for each set of rolls employed, to say nothing of the space occupied by such a mechanism.

It has also become a practice to use an endless music strip with a single tracker-board but in this case, in order to provide a number of selections, a great amount of space must be provided for carrying the endless music strip and this of necessity is a serious offset against the advantages of continuous playing. Furthermore, in such a device, a considerable amount of time is lost in removing played music and inserting a new strip.

The principal object of the present invention is to provide a mechanism which will be of extremely simple and condensed form and will provide for continuous playing of the instrument with but a single music sheet and its winding and re-winding roll or reel.

A further object of the invention is to provide a mechanism which will be driven from a main source of power and in which the driving motor and connections will always rotate in the same direction, thus avoiding the necessity of shifting devices for reversing the movement of the main elements of the device.

A still further object of the invention is to provide for an automatic control of the air passages of the tracker-board with reference to the player pneumatics.

In general, the objects of the invention are to eliminate the complications of the multiple tracker devices, the endless music strip devices and produce with a single music sheet and tracker-range, a continuous or intermittent playing of the instrument as desired, employing a maximum number of selections for a given length of perforated sheet.

The devices embodying the invention are applicable to any type of mechanically operated musical instrument whether it be a piano, piano-player, orchestrion or other wind or string instrument so long as there

is a moving perforated music-sheet employed in conjunction with a tracker.

Referring to the drawings:

Figure 1 is a view somewhat in diagram 5 illustrating the relative position of the various parts of the mechanism in connection with the valve actuators of a wind instrument.

Fig. 2 is a view in front elevation of the 10 music rolls and the winding mechanism therefor shown in enlarged scale as compared with Fig. 1.

Fig. 3 is a detail plan view on enlarged 15 scale of a small section of the tracker-board.

Fig. 4 is a detail view in perspective illustrating the connecting parts of the music- 20 roll and driving shaft for said roll.

Fig. 5 is a detail view in side elevation 25 taken from the right of Fig. 2 with parts broken away to better illustrate the construction.

Fig. 6 is a detail view of one of the music- 30 roll driving gears with its ratchet and pawl.

Fig. 7 is a sectional view taken trans- 35 versely through the music-rolls and tracker-board and a player pneumatic illustrating the control of the ducts of the tracker board.

Fig. 8 is a detail perspective view of the 40 two sections of the shifting valve.

Fig. 9 is a detail side view partially in 45 section and partially in diagram illustrating a modified form of valve chest and player pneumatic in conjunction with the tracker-board and appurtenant parts.

No attempt has been made in the accompanying drawings to show a full musical 50 instrument with its many parts and as the invention relates particularly to the mechanism appurtenant to the tracker-board and 55 music rolls and to the controlling devices for the tracker-ducks, only such mechanism as forms a part of these structures is illustrated and diagrams have been employed wherever a more simplified showing of the 60 connections and mechanisms was possible.

In the accompanying drawings the numeral 1 denotes a base or support having risers 2, 3, provided with suitable bearings for the music rolls 5, 6, which are removably 65 arranged with reference to their bearings. As illustrated, the music roll 5 is made removable through a lug and slot connection, such as illustrated in Figs. 2 and 4, the tubular shaft 7 being held against the compression of a spring 8 so that by an endwise movement the roll 5 may be removed from its end bearing 9.

In ordinary practice, the roll or reel 6 does not have to be removed from the instrument as provision is ordinarily made for attaching the end of the music-sheet to the cylinder of the roll after the music-roll 5 with the sheet has been inserted in its bearings.

The shaft 7 is supported not only in the 65 riser 3 but also in an end-supporting bracket 10 and this shaft has a disk 11 having a comparatively wide peripheral face which is loosely mounted upon the shaft 7. Mounted upon the same shaft 7 and fast thereon is a 70 ratchet-wheel 12 and between said ratchet and the disk 11, there is a gear 13, which is free to rotate on said shaft 7 except when it is connected therewith through a pawl 14 which is pivotally mounted upon the gear 75 13 and is arranged to engage the ratchet 12 as hereinafter more fully described.

The shaft 15 of the roll or reel 6 also has mounted thereon a disk 16 identical in form and construction with the disk 11. This 80 disk is loosely mounted upon the shaft 15 which shaft also has mounted upon it a gear 17. Intermediate the gear 17 and disk 16 is a ratchet wheel 18 which is secured to the shaft 15.

The gear 17, as in the case of the gear 13 is free to rotate on its shaft 15 except when it is connected therewith through a pawl 19 pivoted upon the gear 17 and adapted to be engaged with and disengaged from the 90 ratchet 18.

The friction disk 11 has projecting from it a controlling pin 20 which is arranged to control the position of the pawl 14 with reference to the ratchet 12.

The friction disk 16 has a controlling pin 21 which is arranged to control the engagement and disengagement of the pawl 19 with reference to its ratchet 18.

The gears 13 and 17 are constantly in 100 mesh with intermediate pinions 22, 23, the pinion 23 being a main driving pinion which is connected as illustrated in Fig. 1 with a main driving shaft 24 which in turn is connected with a rotary motor 25.

The motor 25 always rotates in the same direction and the main driving pinion 23 which is in contact with the gear 17 always drives said gear in the direction indicated in Fig. 5 and through the intermediate pinion 22 the gear 13 is always driven in the direction indicated by the arrow. This condition exists with either of said gears, acting as a driving gear when its respective ratchet and pawl is connected with its shaft.

With this arrangement, assuming that the roll 5 is the removable roll which bears the music sheet S and assuming that said music sheet S has already been unwound from the roll 5 and wound upon the roll 6, as it was drawn across the tracker T and assuming that said music sheet S is now being rewound upon the roll 5, it is obvious that the pawl 14 of the gear 13 is in engagement with the ratchet 12 while the pawl 19 of the gear 17 is disengaged from the ratchet 18. Thus, the driving shaft 24 through its pinion 23 and intermediate pinion 22 is driving the

gear 13 and the music roll 5 while the gear 17 is running free upon its shaft 15 permitting the free movement of the music roll 6 (see Fig. 5).

5 This winding of the music sheet in one direction or the other is effected by a mechanism which actuates the friction disks 11 and 16.

Arranged upon the base 1 is a support 26 to which are secured the stationary members 27, 28 of a pair of pneumatic actuators or bellows A, B, their movable boards 29, 30 being connected by an angularly formed bar or lever 31. These pneumatic actuators are 10 subject to inflation and exhaustion and thus the bar 31 in conjunction with the movable board 29 forms a lever for moving a controlling bar 32. This controlling bar 32 projects upward intermediate the friction disks 11 and 16 and has arranged upon either side thereof friction members 33 which, as illustrated, are of curved form and adapted to be pressed against the peripheries of the disks 11, 16 whenever they are moved past 15 a line adjoining the axes of said disks by the movement of the bar 31 and movable board 29.

As the friction disks 11 and 16 are loosely mounted upon their respective shafts 7 and 15 and as each has a controlling pin 20, 21 over-lying the rearward ends of the ratchets 14, 19, it is obvious that upon a collapse of the bellows A, the spring arms 33 of the bar 32 will be forcibly brought into engagement with the peripheries of the friction disks. A partial rotation of said disks with their pins serves to move the pawls 14, 19 either into or out of engagement with their respective ratchets 12, 18. This is clearly indicated in Fig. 5 where the pawl 14 is in engagement with the ratchet 12 and the pawl 19 is disengaged from its ratchet 18. Assume that the friction disks 11, 16 are held or partially rotated by the friction members 33 during the downward movement of the bar 32, the pin 20 will ride along the rearward end of its pawl 14 disengaging said pawl from the ratchet 12. Simultaneously the pin 21 of the disk 16 35 will move toward the forward end of the pawl 19 and will permit said pawl to engage with its ratchet 18. Thus, the roll 5 will be free to rotate while the roll 6 will be driven by its gear 17. Thus, the music roll 55 S will pass over the tracker T from the roll 5 to the roll 6. As soon as the position of the pawls is reversed through the action of the controlling bar 32 and its bellows, the reverse condition will obtain and the music sheet will then be drawn from the roll 6 onto the roll 5.

It will be noted from Figs. 2, 3 and 7 of the drawings that the tracker-board T has a double row of ducts or openings, one row

of ducts t arranged to be operative during 65 the movement of the music sheet in one direction while the other row t' will be operative during the movement of the music sheet in the opposite direction.

The music sheet itself has perforations 70 arranged for each set of tracker-ducts so that one set of selections will be played by the music roll through the tracker-ducts t while said roll is being moved in one direction and a second set of selections will 75 be played by the music sheet S, as its perforations register with the tracker-ducts t' during the reverse movement of the sheet.

This, in conjunction with the mechanism specifically described herein, provides for 80 continuous playing of an instrument and the mechanism heretofore described defines means for driving the main shaft always in the same direction and securing a direct 85 drive effect of either of the music-rolls.

The control of the actuator devices A and B and the consequent control of the friction disks 11 and 16 is effected by mechanism illustrated in Figs. 1, 2, 5, 7 and 8 and this mechanism also controls the two series of 90 tracker-ducts so that the player pneumatics are properly actuated by either set of tracker-ducts dependent upon the direction of movement of the music-sheet S.

The actuators A and B are connected to 95 a valve mechanism C by suitable ducts 34, 35. The duct 34 connects with a port 36 in a stationary block 37 while the duct 35 connects with a port 38 in said block 37. This block 37 has ports 39, 40 connected 100 respectively with the ports 36, 38 and is also provided with ports 41, 42 which, through a channel 43 and conduit 44 connects with the main suction bellows D of the instrument, which, as illustrated, is actuated by 105 a suitable motor.

Overlying the stationary block 37 is a movable valve-block 45 which has ducts and a port 46 opening to the atmosphere and ducts and a port 47 also opening to the atmosphere. Arranged in the bottom face of the movable block 45 and between the two atmospheric ducts 46, 47 is a channel 48 which is adapted to connect either of the ports 39, 41 or the ports 40 and 42 to the main suction duct 44. Thus, by shifting the block 45 either the actuator A or the actuator B may be subjected to suction of the main bellows D and simultaneously as either of said actuators A or B is thus connected, one of the ports 46, 47 is brought into communication with one of the ports 39 or 40 and the corresponding bellows is connected with the atmosphere.

As illustrated in the drawings, the actuator B is subjected to suction while the actuator A is open to the atmosphere.

As a means for shifting the movable block

45, a pivoted lever 49 is connected with said block through a link 50, the upper end of the lever 49 bears a spring-pressed catch 51 and the outer end of the link 50 is connected 5 to a pivoted lever 52 which bears a spring-pressed catch 53.

The music-rolls or spools are each provided with a notch 54, 55 and as the music sheet is unwound from the rolls, either the 10 catch 51 will engage its notch 54 or the catch 53 will engage its notch 55 dependent upon the direction of movement of the music-sheet. As illustrated in Fig. 7, the music-sheet is passing from the roll 6 to the roll 5 and the perforations of the roll corresponding to the tracker-openings t are operated. As soon as the catch 51 engages the notch 54, the valve member 45 will be shifted to the opposite limit of its play and thereupon 15 the actuator A will be collapsed under suction while the actuator B will be inflated. This will pull down upon the controller bar 32 shifting the friction disks to release the pawl 14 from its ratchet 12 and engage the pawl 19 with its ratchet 18. The music-sheet will thereupon immediately change its 20 direction of movement and the roll 6 will become the winding roll while the roll 5 will run free. Simultaneously with this movement 25 the tracker-ducks corresponding to the tracker-openings t will become ineffective for actuating the player-pneumatics and the tracker-ducks t' will become active. The tracker-ducks and their action upon the 30 player pneumatics is also controlled by the valve C and actuators A and B through an independent valve mechanism E. This valve mechanism E is common to all of the player pneumatics, it being understood, of course, 35 that there are two tracker-ducks for each player pneumatic, said ducts corresponding respectively to the series of tracker-openings t and t' .

For controlling the tracker-ducks of the 40 respective series of tracker-openings t , t' , there is illustrated particularly in Figs. 1 and 7 of the drawings, a valve mechanism which is automatic in its action and is controlled through the actuators A and B 45 and the air connections of the valve mechanism C to place either the series of tracker-ducks t or the series of tracker-ducks t' in playing communication with the player pneumatics P. It is to be understood that 50 there is a player pneumatic for each note of the instrument and a tracker-duct connection 56 from each of the tracker-openings t and a tracker-duct connection 57 for each of the tracker-openings in the series t' , which 55 tracker-ducks actuate the valves 58 of the player pneumatics P dependent upon which direction the music-sheet S is moving. The 60 tracker-ducks actuate the valves 58 of the player pneumatics P dependent upon which direction the music-sheet S is moving. The valve chest E has a main suction chamber 59 which is in communication with the main

suction bellows D of the instrument through 65 a duct 59^a. (See Fig. 1). This chamber 59 communicates through an opening 60 with wind-trunks 61, 62 dependent upon the position of a shifting valve 63 which controls ports 64, 65 opening from the channel 60 to 70 the channels 61, 62.

To control the valve 63 and its position, two wind motors 66, 67 or other suitable devices are employed and as illustrated in Fig. 7 the movable boards of the wind-motors or bellows 66, 67 are connected with the spindle 68 which bears the valve 63. The bellows 66 communicates through a duct 69 with the actuator A while the bellows 67 has a duct 70 connecting with the actuator 75 B. It follows that whenever the actuator B, as illustrated in Fig. 6, is subjected to deflation by the suction of the main bellows D of the instrument, the bellows 67 will also be deflated and by a simultaneous action, 80 the actuator A being open to atmosphere will be inflated and the bellows 66, through its duct 69 connecting it with the actuator A will be inflated. Thus the valve 63 will 85 occupy the position illustrated in Fig. 7 closing the port 64.

Assuming that the perforations of the sheet are opening the tracker-ducks t to atmospheric pressure, a diaphragm 71 covering a chamber 72 which, through a bleed-hole 73 communicates with the suction chamber 62, will be released by the admitting of atmosphere to the chamber 72 which will 90 break the suction in said chamber. Thereupon, the valve 58 will shift from its seat 74 100 and subject the player pneumatic bellows p' of the player pneumatic P to the main suction of the instrument through the wind-trunk 59 and appurtenant connections until 105 the music sheet closes the tracker-ducks T. Obviously, the tracker-ducks t will thus be operative so long as the valve 63 closes the port 64.

As soon as the bellows A is deflated and 110 the bellows B expanded, the bellows 66 will be deflated and the bellows 67 will be expanded shifting the valve 63 to open the port 64 and close the port 65. Thereupon 115 the valves 58 of the player pneumatics will be shifted to close the ports 75. Thereupon, the series of tracker-ducks t' will become operative with reference to the player pneumatics P and by breaking the exhaust of the chamber 76 under the diaphragm 77, the 120 valve 58 will be raised to open the port 75 and collapse the bellows p' whenever the tracker-ducks t' are open.

As illustrated in Fig. 1, two sets of player pneumatics P are illustrated with their various connections to the tracker-ducks indicated in diagram and shown as controlling the valves of two distinct sets of wind-chests, the valves appurtenant to the chest X. 125

being open while those appurtenant to the chest Y are closed. This merely illustrates a possible connection of the player pneumatics of a wind instrument and obviously, any desired form of connection may be employed between the player pneumatics and the sounding device.

It is also to be understood that the specific method of shifting the valve mechanism C illustrated herein is merely a form of shifting device which may be employed and that any of the well-known shifting devices, such as commonly employed in instruments of this class may be used in lieu thereof.

In Fig. 9 of the drawings there is illustrated a simple modified form of controlling valve for the tracker-ducks which obviates the use of the specific form of air-motors 66, 67 and shifting valve 63 heretofore described. In this modification, the bellows 100 and 101 are illustrated in dotted outline to save confusion, the bellows 100 being shown as collapsed and subject to the main suction through a duct 102, while the bellows 101 is open to the atmosphere through a duct 103. The ducts 102, 103 communicate with a valve mechanism 104 identical with that heretofore illustrated and described.

The tracker-duct controlling valve Z has a duct 105 communicating with the collapsed bellows 100. The duct 106 communicates with a valve chamber 107 which is covered by a diaphragm valve 108 and the duct 105 communicates with a valve chamber 109 which has a diaphragm valve 110. The diaphragm 108 controls the communication between two passages 111 and 112. The passage 111 is in communication with a tracker-duct 113 while the passage 112 is in communication with a duct 114 leading to the player pneumatic.

The diaphragm valve 110 controls two passages 115, 116. The passage 115 communicates with a tracker-duct 117 while the passage 116 communicates with the duct or wind-trunk 114 of the player pneumatic.

The chamber 109 being under suction inasmuch as it is in connection with the collapsed bellows 100 and through said bellows 50 with the main suction of the instrument raises the diaphragm 110 and establishes communication between the tracker-ducts 117 and the player pneumatic duct 114. The bellows 101 being expanded and subject to 55 atmospheric pressure, the diaphragm valve 108 is closed and breaks the communication between the passages 111 and 112.

Thus, the tracker-ducts 117 are in playing position with reference to the player pneumatics and whenever a tracker-duct is 60 uncovered by a perforation in the music sheet, a valve-chamber 118 will be subjected to atmospheric pressure, whereupon its diaphragm valve 119 which controls a valve

120 will rise, opening a port 121 and closing an air-port 122. The port 121 communicates with an exhaust wind-trunk 123 and as the port 121 is uncovered, the bellows 124 of the player pneumatic will be collapsed. A bleed-hole 125 provides for 70 equalizing the pressure above and below the diaphragm valve 119 when the tracker-ducks 117 are closed. Thereupon, the valve 120 will close the port 121, open the atmospheric port 122 and inflate the bellows 124.

It will be seen from the above description that the valve mechanism Z through its connection with the bellows 100 and 101 will connect either one or the other of the series of tracker-openings corresponding to the 80 ducts 113, 117 directly with the valve chambers 118 of the player pneumatics and while one series of tracker-ducks is thus open and effective for playing operations, the other 85 is closed.

It will be noted that in the form first described or in the above modified form for controlling the two distinct series of tracker-ducks, that the control is intermediate the player pneumatics and the main 90 exhaust of the instrument so that the tracker-ducks are connected directly to the player pneumatics to release and subject them individually to suction while the valve mechanism controls the main suction with 95 reference to either series of tracker-ducks. There is an obvious advantage in this arrangement inasmuch as the tracker-ducks may be permanently connected into the 100 player pneumatics and very simple wind-trunks may be utilized which are common to all of the pneumatics and which are definitely and accurately controlled by a single valve mechanism for all of the pneumatics and the various series of tracker-ducks.

Obviously, it is perfectly feasible and possible to utilize this same valve mechanism any number of tracker-boards each having an independent music sheet. This would give the same number of selections but, of course, would require merely a duplication 110 of the winding and re-winding mechanism for each roll.

Obviously, many modification of the arrangement of the mechanism herein illustrated and described may be made without departing from the spirit or intent of the invention and a plurality of series of tracker-ducks may be equally well controlled by a 120 valve mechanism embodying the same elements and principles as herein defined.

What I claim as my invention and desire to secure by Letters Patent is:

1. In a device of the character described, 125 a pair of music-rolls, each having a driving shaft, a driving gear on the shaft of each music-roll, a main driving shaft, a gear on said shaft constantly connected with both of

- 5 said gears, a clutch device intermediate each of said driving gears and its respective shaft and automatic means for simultaneously connecting one of said clutch devices and releasing the other of said clutch devices.
- 10 2. In a device of the character described, a pair of music-rolls, each having a driving shaft, a driving gear on the shaft of each music-roll, a main driving shaft, a gear on said shaft constantly and permanently gear-connected with both of said gears, a clutch device intermediate each of said driving gears and its respective shaft and automatic means for simultaneously connecting one of 15 said clutch devices and releasing the other of said clutch devices.
- 15 3. In a device of the character described, a pair of music-rolls, each having a driving shaft, a driving gear on the shaft of each music-roll, a main driving shaft, a gear on said shaft and gears connecting said gear constantly with both of said driving gears, a clutch device intermediate each of said driving gears and its respective shaft and friction devices for controlling the clutches.
- 20 4. In a device of the character described, a pair of music-rolls, each having a driving shaft, a driving gear on the shaft of each music-roll, a main driving shaft, a gear on said shaft and intermediate gearing constantly connecting said shaft with both of said driving gears, a clutch device intermediate each of said driving gears and its respective shaft and friction devices for 25 automatically controlling the clutches.
- 25 5. In a device of the character described, a pair of music-rolls, each having a driving shaft, a driving gear on the shaft of each music-roll, a main driving shaft, a gear on said driving shaft and intermediate gearing constantly connecting said shaft with both of said driving gears, a clutch device intermediate each of said driving gears and its respective shaft, a friction device for 30 controlling the clutches and a pneumatic motor for actuating said friction device.
- 30 6. In a device of the character described, a pair of music rolls, a driving shaft for each of said rolls, a driving gear for each of said shafts, a main driving shaft, a gear on said main shaft and intermediate gearing constantly connecting said shaft with each of said driving gears, means for 35 clutching and releasing said driving gears with reference to their respective shafts and means for alternately actuating the clutching and releasing mechanism of each shaft.
- 35 7. In a device of the character described, a pair of music rolls, a driving shaft for each of said rolls, a driving gear for each of said shafts, a main driving shaft, a gear on said main driving shaft constantly in intermeshing engagement with each of said driving gears, means for clutching and releasing either of said driving gears with reference to their respective shafts and pneumatic means for alternately actuating the clutching and releasing mechanism of each shaft.
- 40 8. In a device of the character described, a pair of music rolls, a driving shaft for each roll, a driving gear for each shaft, a main driving shaft, a gear on said driving shaft having constant intermeshing engagement with both of the said driving gears, a clutch device intermediate each of said gears and its driving shaft, a friction disk for each shaft controlling the respective clutch devices, a pneumatic motor for controlling said friction disks, a valve for controlling the operation of said motor and means intermediate the music rolls and valve for actuating said valve.
- 45 9. In a device of the character described, a pair of music rolls each having a driving shaft, a driving gear on the shaft of each music roll, a ratchet and pawl intermediate each of said gears and its respective shaft, a friction disk controlling the position of the pawls with reference to the ratchets, a friction member controlling the movement of the friction disk and a pneumatic for automatically controlling the friction member.
- 50 10. In a device of the character described, a pair of music rolls each having a driving shaft, a driving gear on the shaft of each music roll, a ratchet and pawl intermediate each of said gears and its respective shaft, a friction disk controlling the position of the pawls with reference to the ratchets, a friction member controlling the movement of the friction disks and a pneumatic for automatically controlling the friction member and valve connections operable from the music roll for controlling a pneumatic.
- 55 11. In a device of the character described, a pair of music rolls, a driving member for each of said rolls, a driving shaft, means for driving said shaft always in the same direction and which is always in driving connection with both of said members and automatic means for simultaneously connecting one of said members and disconnecting the other of said members from driving connection with its corresponding music roll.
- 60 12. In a device of the character described, a pair of music rolls, a note sheet to be wound from one of said rolls to the other and a driving member for each of said rolls, a driving shaft, means for driving said shaft always in the same direction and which is always in driving connection with both of said members and automatic means for simultaneously connecting one of said members and disconnecting the other of said members from driving connection with its

corresponding music roll when the note sheet has completed its travel from one of said rolls to the other.

13. The combination with a pair of music rolls and a note sheet adapted to be wound from one of said rolls to the other, of a driving member for each of said music rolls, and a clutch on each of said members and its corresponding music roll, a power driving shaft, means for driving said shaft always in the same direction and which is always

in driving connection with each of said members and means for automatically bringing one of said clutches into action and throwing the other clutch out of action, ¹⁵ said means being controlled by the position of the note sheet with relation to said music roll.

CARL M. WELTE.
